US0D1056973S

(12) **United States Design Patent** (10) Patent No.: **US D1,056,973 S**
 Prochaczka (45) Date of Patent: ** Jan. 7, 2025

(54) **OPERATING CONSOLE FOR MACHINE TOOL**

(71) Applicants: **DMG MORI CO., LTD.**, Nara (JP); **GILDEMEISTER Beteiligungen GmbH**, Bielefeld (DE)

(72) Inventor: **Matus Prochaczka**, Lochau (AT)

(73) Assignees: **DMG MORI CO., LTD.**, Nara (JP); **GILDEMEISTER Beteiligungen GmbH**, Bielefeld (DE)

(**) Term: **15 Years**

(21) Appl. No.: **29/819,097**

(22) Filed: **Dec. 13, 2021**

(30) **Foreign Application Priority Data**

Jun. 15, 2021 (JP) ..... 2021-012788 D

(51) **LOC (15) Cl.** **15-09**

(52) **U.S. Cl.**

USPC **D15/138**; D14/371

(58) **Field of Classification Search**

USPC D13/162, 162.1; D15/138; D14/341, D14/371, 374, 388, 390-393, 396, 399, D14/400

CPC H04N 1/00013; H04N 1/00082; H04N 1/00896

(57) **CLAIM**

The ornamental design for an operating console for machine tool, as shown and described.

DESCRIPTION

FIG. 1 is a front view of an operating console for machine tool in accordance with an embodiment of my new design; FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines shown in the figures depict portions of the operating console for machine tool that form no part of the claimed design.

1 Claim, 5 Drawing Sheets
